(57) **CLAIM**

The ornamental design for a strap-on identification holder, as shown and described.

DESCRIPTION

FIG. 1 is a front perspective view of a strap-on identification holder incorporating our new design;

FIG. 2 is a rear perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof;

FIG. 8 is a rear side view thereof;

FIG. 9 is a front view thereof with detached straps; and,

FIG. 10 is a rear view thereof with detached straps.

The broken lines shown in the drawings illustrate portions of the strap-on identification holder that form no part of the claimed invention. The larger dashed lines around the outer perimeter of the holder represent top stitching.
